UNITED STATES PATENT OFFICE.

GEORGE FREDERICK JORDAN, OF PHILADELPHIA, PENNSYLVANIA, AS
SIGNOR TO THE MACKELLAR, SMITHS & JORDAN COMPANY, OF SAME
PLACE.

DESIGN FOR A FONT OF PRINTING-TYPE.

SPECIFICATION forming part of Design No. 19,257, dated August 6, 1889.

Application filed May 6, 1889. Serial No. 309,822. Term of patent 14 years.

To all whom it may concern:

Be it known that I, GEORGE FREDERICK JORDAN, a citizen of the United States, and a resident of Philadelphia, Pennsylvania, have invented a new and original Design for Type, of which the following is a specification.

My design for a font of type is clearly shown in the annexed typographical impression.

The leading feature of the design is the character of the light lines of the letters, these being much heavier than usual in type of this general style, so that the letters present an appearance somewhat resembling that of solid letter type—that is to say, type having all the lines of the letters of uniform thickness—this appearance, however, being

gained without losing the graceful character of the type, due to a distinction between the lines of the letters. The general heavy character of the light line is carried out in the figures as well as in the letters.

I claim—

The design for a font of type, as described and shown in the annexed typographical impression.

In testimony whereof I have signed my name to this specification in the presence of two subscribing witnesses.

GEORGE FREDERICK JORDAN.

Witnesses:

WILLIAM D. CONNER,
HENRY HOWSON.
